UNITED STATES PATENT OFFICE.

WARREN WAGNER, OF BURKBURNETT, TEXAS.

UNDERREAMER.

1,149,799.

Specification of Letters Patent. Patented Aug. 10, 1915.

Application filed April 23, 1913, Serial No. 763,164. Renewed April 24, 1915. Serial No. 23,769.

To all whom it may concern:

Be it known that I, WARREN WAGNER, citizen of the United States, residing at Burkburnett, in the county of Wichita and State of Texas, have invented certain new and useful Improvements in Underreamers, of which the following is a specification, reference being had to the accompanying drawings.

10 This invention relates to improvements in underreamers such as are employed for reaming wells beneath the lower end of a tube or casing, the invention having for its primary object to increase the durability, 15 efficiency and general serviceability of the underreamer disclosed in my Patent Number, 1,080,666, issued December 9, 1913.

Another object of the invention resides in the provision of improved means for seating 20 the bits or cutters when in their operative positions against the bottom of the mandrel, whereby separation or spreading of the bits is rendered impossible and a very rigid and durable structure obtained.

25 The invention further resides in the improved form and construction of the cutting bits, and means for connecting the same to the spring pressed plunger or stem mounted within the mandrel or body of the tool.

30 With the above and other objects in view as will become apparent as the description proceeds, the invention consists in certain constructions, combinations and arrangements of the parts that I shall hereinafter 35 fully describe and claim.

For a full understanding of the invention, reference is to be had to the following description and accompanying drawings, in which—

40 Figure 1 is a side elevation of an underreamer embodying the present invention; Fig. 2 is a view looking at right angles to Fig. 1 showing the positions of the cutting bits as the same are being lowered into the well casing. Fig. 3 is a longitudinal section; Fig. 4 is a section taken on the line 4—4 of Fig. 3; Fig. 5 is a bottom plan view of the body of the mandrel; Fig. 6 is a detail perspective view of one of the cutting 45 bits; Fig. 7 is a similar view of the key; Fig. 8 is a perspective view of a modified form of the cutting bit. Fig. 9 is a detail fragmentary elevation illustrating a slightly modified means of shouldering the cutting 50 bits against the lower end of the mandrel.

Referring in detail to the drawings, 5 designates the stock or mandrel which is longitudinally bored as indicated at 6, the upper end of said bore being enlarged as at 7 for a purpose which will be later referred to. 60

The mandrel is provided upon opposite sides with channels 8 and a longitudinal slot 9 connects these channels with the bore of the mandrel. The lower end of this slot 65 is widened or flared as indicated at 10 and the opposed walls of the channels are provided with longitudinal grooves 11. The inner walls of these grooves are inwardly inclined as shown at 12, whereby the grooves 70 are widened at their lower open ends. Inclined notches or recesses 13 open into the guide grooves 11 at the upper ends of the inclined walls 12 thereof. The lower end of the stock or mandrel is provided with a 75 central longitudinally extended web 14, the lower end of which is beveled in opposite directions as indicated at 15. Upon each side of this web, and at opposite sides of the channels 8, the lower end of the mandrel 80 is formed with the lugs 16, the inner faces of which are obliquely inclined or beveled as at 17. From the upper ends of these inclined faces, the lower surface of the mandrel 85 is curved or convex to the point of its junction with the web 14 as shown at 18. The purpose of this particular construction of the mandrel will be more fully referred to in the following description.

The cutting bits illustrated in detail in 90 Fig. 6 each consists of the bit blade or body 19 which has formed upon one of its ends a longitudinally extended rectangular shank 20. The outer face of the bit body is convex 95 and is slightly inclined outwardly with relation to the longitudinal axis of the shank. The lower end faces of the bit blades are transversely inclined and are slightly concaved as shown at 21, while the inner faces of said blades are inclined as shown at 22, 100 said inclined faces diverging from the web 14 on the lower end of the mandrel when the bits are mounted therein. Said inclined faces of the bits terminate at one of their ends at a point adjacent the upper end of 105 the bit body, from which point, the inner faces of the bits are longitudinally extended as at 23 for engagement with the web 14. The upper end of the body of each bit upon 110 opposite sides of the shank 20 is provided

with an abutment lug 24 having a beveled or inclined face 25 for engagement with the beveled face 17 on one of the lugs 16 formed upon the mandrel. Each lug 24 is also provided with a curved or concave face 26 to engage the convex faces 18 of the mandrel 5. It will thus be apparent that when the bits are in their cutting positions, as shown in Fig. 1, the lugs 16 against which the 10 abutment lugs 24 on the cutting bits engage will effectually prevent relative lateral spreading movement of the cutting bits.

Upon the opposite faces of each of the bit shanks 20, the longitudinally extending ribs 27 are formed and these ribs are adapted to be received in the grooves 11 provided in the opposed walls of the channels 8. Upon the end of the shank 20 and projecting from its opposite faces, the semi-cylindrical lugs 28 are formed which are also adapted for movement in the grooves 11. These lugs are adapted to be passed through the notches or recesses 13 when the bits are fitted in the mandrel and when in position, the plane faces of the lugs are opposed to said recesses. As the upper and lower walls of these recesses are beveled or inclined, all liability of the lugs 28 moving outwardly through said recesses when the bits are extended, for 30 the insertion of the tool in the well tube, is obviated.

29 indicates the spring pressed stem or plunger which is arranged in the bore 6 of the mandrel or stock, and 30 designates the 35 spring arranged thereon. One end of this spring engages the head 31 on the upper end of the stem while the other end of said spring bears against the lower end wall of the enlarged portion of the bore 6. This 40 stem is provided in its lower end with an opening 32 and each of the bit shanks 20 is also provided in its upper end with a rectangular opening 33, the opening in one shank, however, being somewhat larger than the 45 opening in the other shank.

34 designates the pin or key which tapers in width longitudinally. This key is centrally provided upon one of its longitudinal edges with a lug or extension 35 which is 50 adapted to be received in the opening 32 provided in the spring pressed stem or plunger. The lug 35 on the key effectually prevents longitudinal movement of said key in either direction through the openings 33 in 55 the cutting bits, thus eliminating all liability of disconnection of said bits from the plunger 29. It is of course understood that the larger opening 33 is equivalent in depth to the width of the central portion of the key 60 whereon the lug 35 is formed so that said key may be readily inserted through said latter opening and the lug 35 engaged in the opening 32 of the plunger. The bit having the larger key receiving opening 33 is provided 65 with a pin 39 extending transversely

of said opening, said pin acting as a wedge for the key 34 to prevent the same from working loose.

The web 14 formed on the lower end of the mandrel or stock is provided with a central longitudinally extending opening 36 in which a rod 37 is loosely disposed. The upper end of this rod is threaded in the lower end of the spring pressed plunger or stem 29. The lower end of this rod is provided 75 with a suitable eye 38.

In the use of my improved underreamer for reaming the walls of wells beneath the casing or well tubing, the rod 37 is pulled downwardly, thereby moving the plunger 80 or stem 29 against the tension of the spring 30, whereby the shanks of the cutting bits are permitted to move downwardly in the channels 8, the body portions of the cutting bits moving inwardly beneath the lower edge 85 of the web 14 into engagement with each other. This inward movement of the bits is permitted by the provision of the inclined inner walls 12 of the grooves 11, the inner faces of the bit shanks 20 being inclined as 90 indicated at 20°. It will be understood that the ribs 27 of the cutting bits fit loosely in the slots 11 of the mandrel, and in view of the tapering form of the key 34, one of the bits will shift slightly longitudinally upon 95 the end of the key, while the other rocks upon the pin 39 as the bits are forced inwardly toward each other. After disposing the bits in this manner they are inserted into the well tubing and forced downwardly 100 therein, the upward pull upon said bits exerted by the spring 30 tending to move the bits outwardly into frictional engagement with the well casing. Each of the bit shanks is further provided upon its outer face with a shoulder 20°, and these shoulders are 105 adapted for engagement with the lower edge of the well tube when the bits are disposed beneath the same in their operative positions as shown in Fig. 3, the spring 30 acting to force the stem 29 upwardly in the mandrel and thereby throw the body portions of the bits outwardly upon opposite sides of the web 14 and into engagement with the walls 110 of the well. When the reamer is rotated, in the ordinary manner, the walls will be reamed or cut away beneath the lower end of the casing or tube.

In Fig. 8 of the drawings, I have shown a slightly modified form of the cutting bits wherein the same are provided with longitudinal inner faces 21' at the upper ends of which the inclined shoulders 22' are formed. Beyond these shoulders, the bits are provided with plane faces extending the entire width of the body portions of the bits for engagement with the web 14. It will be understood that the inclined shoulders 22' engage the beveled surfaces 15 on the lower edge of said web. In this form of the bit, 120 125 130

the body thereof is cut away or reduced in thickness as indicated at 40, whereby a more extensive cutting edge is provided upon the lower surface of the bit and a recess or chamber is provided between the opposed body portions of the bits in which the cut material may collect, thereby relieving the bits of excessive wear. The manner of seating the bit against the lower face of the mandrel or stock is precisely the same as that described in connection with the preferred form of the cutting bit.

In Fig. 9, I have illustrated a slightly modified manner of seating the cutting bits against the bottom face of the mandrel when the same are in their operative positions. In this construction the mandrel is provided upon opposite sides of its central depending web and on each side of the bit receiving 20 channels with oppositely inclined faces 41 to receive the correspondingly inclined upper faces 42 which are provided upon the body portions of the cutting bits. It will thus be seen that a bearing face of comparatively 25 extensive area is provided for the cutting bits so that the same are greatly strengthened and braced during their cutting action.

From the foregoing, it will be seen that I have greatly improved the construction of 30 the underreamer as shown in my prior application for patent hereinbefore referred to, and materially increased its operating efficiency and durability, the bits being seated against the lower end of the mandrel in such 35 manner as to cause the same when subjected to longitudinal pressure to bear against the convex faces 18 of the mandrel which tends to force the bits upwardly and outwardly, thereby relieving the inner faces of the bits 40 which engage the web 14, of undue friction, and maintaining a smooth bearing surface for the bits. When the reaming operation is completed, the reamer may be readily withdrawn by simply pulling upwardly upon the 45 same. The shoulders 20^a of the cutting bits engaging the lower end of the well tubing holds the bits while the mandrel moves upwardly within the lower end of the tube.

When the lower edge of the depending flange 50 or web 14 reaches the point of juncture of

the shanks with the body portions of the cutting bits, the beveled or inclined faces 20' of said shanks move inwardly against the opposite sides of said web thus permitting the cutting bits to be drawn upwardly with- 55 in the lower end of the well tube.

The device as a whole is comparatively simple in construction and the various parts thereof may be easily and quickly assembled or disassembled when it is necessary to 60 sharpen the cutting bits.

It will be seen that I have made no material additions to the construction of my invention as shown in the prior application and it will therefore be appreciated that the 65 improved device may be manufactured with practically no increase in cost.

While I have shown and described the preferred form and construction of the several elements employed, it will be obvious that 70 the same are susceptible of considerable modification in the form, proportion and arrangement thereof without departing from the essential features or sacrificing any of the advantages of the invention. 75

Having thus described the invention, what is claimed is:

In an underreamer, a mandrel, opposed cutting bits longitudinally movable in the mandrel, and fastened to said mandrel by 80 bayonet slots therein and lugs on said bits, each of said bits having a portion projecting beyond the periphery of the mandrel, a spring pressed stem mounted in the mandrel and provided with a rectangular opening, each of said bits also having a rectangular opening, a key insertible through the openings in the cutting bits and said stem, and means removably mounted in the projection on one bit to positively lock the key 90 against longitudinal movement through said openings, said means being removable from the bit while the same is in its normal position in the mandrel.

In testimony whereof I hereunto affix my 95 signature in the presence of two witnesses.

WARREN WAGNER.
